UNITED STATES PATENT OFFICE

2,512,214

DRY FEED MIXER

Samuel D. Riza, Cleburne, Tex.

Application April 1, 1949, Serial No. 84,955

2 Claims. (Cl. 259—97)

1

This invention relates generally to devices for mixing various types of feeds, grains, fodder, forage, cereals, and the like, and more particularly to a dry feed mixer which is especially well, although not exclusively, suited for use in connection with a sweet feed mixer such, for example, as that disclosed in the U. S. Patent Number 2,164,257 to T. H. Riza.

Machines for mixing dry feeds and the like are well known, and in machines of this character heretofore devised for the purpose it generally has been the practice as disclosed, for example, in the U. S. Patent Number 2,113,914 to H. G. Day to employ a fixed tube within which a screw-type conveyor and elevator operates to elevate and circulate the ingredients to be commingled in the mixing process. In the circulation of the ingredients, the same are moved from the top of the tube downwardly within a material receiving chamber or tank having a funnel or inverted cone-shaped lower wall portion which defines a feed intake opening with respect to the lower portion of the elevator tube and through which the feeds must pass for re-circulation through the elevator tube.

Various types of feeds, however, require different intake openings to the elevator tube for quality and economy in the mixing operation which thus normally requires in the fixed tube machine a separate machine for each type of feed to be mixed, that is, for example, one machine for mixing small grains or fine heavy feeds and another machine for mixing light bulky feeds.

In the prior art machines, the single type of feed to be mixed therein determined the size of the intake opening between the bottom of the elevator tube and the funnel, and thus a machine with a fixed tube set to mix small grains and fine heavy feeds, for example, will not mix light bulky feeds for the reason that the small intake opening desirable for picking up the fine heavy feeds causes blocking of the light bulky feeds with the result that circulation of the feeds may be substantially completely prevented. Moreover, a fixed tube machine made to mix dairy ration, for example, will not properly clean out when egg mash, chick starter, scratch, or like feeds, are mixed therein.

According to the arrangement of the present invention, and as an important object and feature thereof, the foregoing difficulties and disadvantages of the prior art machines are obviated by the provision of a sectionalized elevator tube having an adjustable telescopically mounted

2

portion which is constructed and arranged to be raised and lowered at will to regulate the size of the feed intake opening thereto according to the type of feed to be mixed whereby the mixing machine of the present invention is universally applicable and useful for mixing substantially all types and kinds of feeds therein.

As another feature and object of the present invention, after dry mixing, provision is made for complete and efficient cleaning of the ingredients in the tank through a novel adjustable discharge valve and horizontally disposed conveyor tube interconnecting the dry mixer of the present invention with the sweet feed mixer of the aforementioned patent to T. H. Riza. By reason of this arrangement, the materials are transferred from one mixer to the other merely by opening the discharge valve according to a desired discharge rate, without requiring further labor involved in handling the materials or further attention to the machine in contradistinction to the prior art machines wherein the mixed materials to be sweetened are elevated by separate machinery from a discharge chute at the bottom of the cone or funnel of the dry mixer to the intake or hopper at the top of the sweet feed mixer.

As a further object and feature of the present invention, provision is made for lowering the adjustable elevator tube portion as the feed discharge operation nears completion, thereby assuring and facilitating complete cleaning out of materials in the mixing chamber.

As an additional feature and object, provision is made for assuring and facilitating complete delivery to the mixing chamber of all feeds received in the elevator tube, this being accomplished by a novel adjustable intake valve located on the elevator tube in the lower end portion thereof disposed within the feed receiving hopper of the machine and by the further provision of a novel toggle type lock for this valve whereby the same be set and maintained in any position from full closed to full open.

The foregoing and additional objects, features, improvements and advantages of the present invention will become more clearly apparent as the specification proceeds, the invention comprising the construction, arrangement and combination of parts as now fully to be described and as hereinafter to be specifically claimed, it being understood that the disclosure herein is merely illustrative and intended in no way in a limiting sense.

In the accompanying drawings forming a part of the specification:

Figure 1 is a view in elevation of the dry feed mixer of the present invention in working association and combination with the sweet feed mixer of the aforesaid patent to T. H. Riza;

Figure 2 is a fragmentary elevational view of the dry feed mixer as seen along the line 2—2 of Figure 1;

Figure 3 is a rear view of the mixer as seen in Figure 2;

Figure 4 is a top view of the mixer as viewed from the top of Figure 3;

Figure 5 is a sectional view taken along the line 5—5 of Figure 4;

Figures 6 and 7 are fragmentary sectional views taken respectively along the lines 6—6 and 7—7 of Figure 5;

Figure 8 is a perspective view of the upper portion of the elevator tube and its associated parts;

Figure 9 is a sectional view taken along the line 9—9 of Figure 5, and

Figure 10 is a fragmentary sectional view, somewhat enlarged, of the elevator and horizontal discharge tubes taken along the line 10—10 of Figure 9, parts of the elevator tube being shown in elevation.

Referring now to the drawings wherein like characters of reference denote like parts throughout the several views, and more particularly to Figure 1, there is shown thereon, a platform 15 which is supported from the ground as by the uprights 16.

Supported on platform 15 is a sweet feed mixer generally designated by the numeral 17 and having a feed receiving hopper 18 which is interconnected as by the longitudinal tube 19 with the dry feed mixer generally designated 20 and also supported on platform 15. Mixer 17 is a device for mixing the feeds, or cereals, or the like, received from mixer 20 with molasses, syrups or the like, all for the specific purposes and in the specific manner and by the specific means set forth in particularity in the aforesaid patent to T. H. Riza and reference may be had thereto for further details of construction and operation of a sweet feed mixer suitable for operation with the dry feed mixer 20.

Mixer 20 comprises a material receiving chamber or tank having the upper cylinder or drum 21 supported above the platform 15 as by the plurality of uprights or posts 22. Drum 21 preferably is provided with a plurality of inspection plates, windows, or the like 23 which also may be used to pipe feed from the dust collector into the tank direct from the mill.

Drum 21 of the tank has a funnel or inverted cone-shaped portion 24 depended therefrom which terminates in a spout or lower cylindrical tube portion 25 of the tank.

Tank portion 25 comprises a portion of the sectionalized feed elevator tube 25, 26, 27 within which the vertical screw conveyor 28 is mounted for rotation, to which end or purpose, tube section 25 is extended approximately nineteen and one half inches below the platform and is provided with a feed receiving opening 29 which extends substantially the full length of the lower side wall portion thereof below the platform.

Tube section 25 is closed at the bottom by a base plate 30 and a chute or hopper 31 preferably is welded to the base plate and tube and extends to an opening, not shown, in the platform through which the grain is admitted to the chute and

thence into the tube 25 through opening 29 therein.

Opening or feed intake 29 preferably is closed as by the arcuately shaped sliding door 32 which is interfittingly mounted with respect to the side wall of tube 25, i. e., concentrically disposed with respect thereto whereby a locking bar or rod 33 for the door is effective in tightly sealing and holding the door in perfect alignment with the tube in any position from full closed to full open. To this end, rod 33 is pivotally supported at the floor or platform level as by brackets 34 and 35 and is provided with an offset central portion 36 which is yieldably urged against the door by gravity acting thereon, the point of contact of the offset portion with the door being above the pivot axis of the rod whereby the offset portion in response to any tendency of the door to slide downward from a pre-set position follows the downward movement of the door but also moves radially to force the door into tightly sealing relation with tube 25 and thus substantially immediately and effectively arrests the tendency of the door to slide downwardly. Thus, the locking bar 33 acts like a toggle and is effective to lock the door in any of the many positions to which it may be adjusted according to the desired rate of feed intake to the elevator tube.

Door 32 and lock 33 preferably are provided with handle portions 37 and 38 respectively to facilitate sliding and unlocking operations thereof.

Tube section 26 is telescopically supported in tube section 27 so that the distance between the lower end of section 26 and the upper end of the tube section 25 at the junction of cone or funnel 24 therewith may be varied as much as twenty-four inches in order to provide an optimum opening between the elevator tube and the tank according to the character of the feed to be circulated therebetween.

Tube section 26 is adjustably secured to section 27 for sliding movement therein by means of the elongated angle irons 39 and 40, the lower ends of which are secured to section 26 in diametrically opposed relation as by cotter pins 41 and 42. Angle irons 39 and 40 are slidably received in the slide guides 43 which are secured to the outer telescoping member or tube section 27 as by being welded thereto. Section 27, in turn, is secured as by the horizontally disposed brackets 45 and 46 to the drum 21 concentrically and coaxially therewith.

Angle irons 39 and 40 serve as racks for coaction respectively with the gear segments 47 and 48 which are secured to a shaft 49 for rocking movement therewith to elevate or lower the angle irons, as the case may be. To this end, the angle irons preferably are provided with a plurality of apertures 50 which serve as teeth for coaction with the teeth of the gear segments.

Shaft 49 is journaled in a pair of brackets 51 and 52 which are secured as by welding to the tube section 27.

Shaft 49 is coupled as at 53 to an extension shaft 54 which is journaled near the outer end thereof in a bracket, not shown, secured to drum 21. A sprocket 55 is secured to shaft 54 and an endless chain 56 is trained thereabout and also about a drive sprocket 57 to which an operating handle 58 is secured, the sprocket 57 being journaled on funnel 24 in any suitable manner, not shown.

A dog 59 is pivotally supported as at 60 on funnel 24 for releasable locking engagement with

chain 56, thereby to lock the inner telescoping tube section 26 in an adjusted position. A pointer 61 carried by the chain and a cooperating scale 62 mounted on drum 21 indicate the amount of opening 63 between tube sections 25 and 26. Handle 58, dog 59, pointer 61 and scale 62 are all within easy reach and view of an operator standing on the platform.

Horizontal connection tube 19 passes through drum 21 and makes connection with tube 27 near the upper portion thereof by means of an upwardly inclined plate 64, formed integrally with tube 19 and connected to tube section 27 and a pair of side plates 65 and 66 secured to tube section 27 and connected to tube 19, plate 65 also being the end closure for tube 19. The tube 19 also comprises an inclined under portion 67 for connection to tube 27 as at 68, thereby to complete the sealed connection or communication between the tubes.

An opening 69 is provided in tube section 27 at this connection to provide the discharge port for the mixed ingredients in the tank, and the rate of discharge through this opening is controlled by the arcuately formed gate 70 which is hingedly secured in matching engagement with the tube wall surrounding opening 69 by means of a rod 71 to which it is secured for rocking movement, rod 71 being journaled in suitable openings therefore provided in plate 65 and 66.

An extension shaft 72 is coupled to rod 71 as at 73 and this shaft is suitably journaled in any convenient manner, not shown, on the drum 21. The extended end of shaft 72 has an arm 74 secured thereto and this arm in turn, has an elongated depending handle 75 pivotally secured thereto as at 76. Thus, by raising or lowering handle 75 which is within easy reach of an operator on the platform, gate 70 may be opened or shut to any desired degree, the gate being held in the adjusted position as by locking the handle to the cottered pin 77, the pin being first inserted through the proper one of the plurality of apertures 78 provided in the handle.

An inspection plate 79 preferably is provided in plate 64 and a horizontal conveyor screw 80 is mounted in tube 19 and has the shaft 81 thereof journaled in plate 65 and extended outwardly of drum 21 wherein it is journaled as at 82 to receive a pulley 83.

Vertical screw conveyor 28 has a shaft 84 which is journaled as at 85 in the top plate 86 for the tank and extends beyond plate 86 to receive a pair of pulleys 87 and 88. Pulley 88 is connected as by an endless belt 89 to pulley 84 for screw 80, suitable idler pulleys 90 being employed to facilitate the driving connection therebetween.

Pulley 87 is connected by an endless belt 91 to a pulley 92 carried on the shaft 93 of an electric motor 94 which is supported as by the brackets 95 on drum 21, both screw conveyors 28 and 80 being driven by the same motor 94.

A slinger 96 may be detachably secured to screw 28 to free the screw of soft feeds and may be removed when mixing grains.

From the foregoing, the operation of the mixing apparatus disclosed should now be clearly apparent. However, it should be briefly stated that the feeds to be mixed in dry mixer 20 are supplied thereto by way of chute 28 from whence the feed enters the elevator tube through opening 29 therein, door 32 being adjusted according to the type of feed and rate of intake desired.

The feed is elevated and mixed in the elevator tube by the vertical conveyor 28 as the same ro-

tates in the tube. When the feed reaches the top of tube section 27 it overflows thereover in all directions and re-enters telescoping tube 26 through opening 63 between tube sections 25 and 26, gate 70 being closed and tube section 26 being adjusted to provide the proper size of opening 63 for the particular feed being mixed.

The feed is thus circulated between the tank and the telescoped tube sections 26 and 27 until thoroughly mixed after which the feed may be discharged into sacks by way of the conventional discharge gate 97, or gate 70 may be opened whereupon the feed is discharged through tube 19 to the sweet feed mixer 17, gate 70 being opened a preferred amount according to the desired rate of discharge of the feed. As the discharge operation nears completion, tubular section 26 is lowered gradually to close opening 63, thereby to facilitate complete cleaning out of the materials in the mixing chamber.

The nicety of the arrangement of racks 39, 40 and the coaxing gear segments 41, 48 in operating while surrounded by feed will be appreciated by those skilled in the art.

Whereas apparatus has been provided which is well adapted to fulfill the aforesigned objects of the invention, various modifications in the construction, operation and arrangement of parts may obviously be made and are contemplated and the right is expressly reserved to make such changes and modifications as fall within the spirit and scope of the invention defined by the appended claims.

What I claim as my invention is:

- 35 1. A dry feed mixer comprising an upright mixing tank having an enlarged upper portion, a restricted lower tubular portion and an intermediate funnel portion connecting the adjacent ends of the upper and lower tank portions, an elevator tube including an upper elevator tube section, means supporting the upper elevator tube section in the upper tank portion and in alignment with the lower tank portion, an adjustable elevator tube section extending between the lower end of upper elevator tube section and the upper end of the lower tank portion and telescopically engaging the upper elevator tube section and contacting the lower tank portion in one of its adjusted positions, said lower tank portion forming a lower section of the elevator tube and having a valve controlled inlet for dry feed to be mixed, a driven screw conveyor in the elevator tube and extending to adjacent the remote ends thereof for elevating the dry feed to the open top of the elevator tube for discharge into the tank, an outlet conduit communicating with and extending from the upper elevator tube section, an adjustable closure regulating the discharge from the upper elevator tube to the outlet conduit, and manually operated means connected to the adjustable elevator tube section to raise said section for adjustably spacing its lower end from the lower tank portion.
- 40 2. A mixing apparatus of the character disclosed comprising, a tank having an upper cylindrical portion, a lower tube portion of smaller diameter and an intermediate converging portion, an elevator tube including said tube portion and a pair of upper and lower telescoping tube sections arranged coaxially with respect to said tube portion, said upper tube section being secured to said tank, means adjustable at will for slidably moving the lower telescoping tube section from a position in which its lower end engages the upper end of said tube portion into a

- 65
- 70
- 75

desired spaced relation with respect to the upper end of said tube portion according to the type of feed to be mixed in the dry mixer, said tube portion having a closed lower end and an inlet opening in its side wall, a sliding closure for said opening, means for retaining the closure in a plurality of positions to completely close, partially close or fully expose the inlet opening, an outlet conduit having an inlet end communicating with said upper tube section, an adjustable gate to 10 completely close, partially close or fully expose the inlet end of the outlet conduit, means adjustable at will for adjusting said gate to a predetermined open position thereby to provide a desired rate of discharge from the upper tube 15

section, and a driven vertical screw conveyor in said elevator tube.

SAMUEL D. RIZA.
